UNITED STATES PATENT OFFICE

NEWTON C. SCHELLENGER, OF ELKHART, INDIANA, ASSIGNOR TO CHICAGO TELEPHONE SUPPLY COMPANY, OF ELKHART, INDIANA, A CORPORATION OF DELAWARE

RHEOSTAT

Application filed October 6, 1926. Serial No. 139,783.

My invention relates to improvements in the electrical art and more particularly to control apparatus such as rheostats and potentiometers.

5 I propose in general to provide a greatly improved rheostat which is not only substantially moisture proof but is adapted to withstand severe service and usage, such as is commonly experienced in radio apparatus.

10 In this rheostat of my invention, I employ an insulator strip rendered moisture proof by a preservative such as linseed oil. This strip is preferably treated in accordance with my novel process which includes impregnating 15 the strip with linseed oil and subsequently tumbling the strip in a tumbler to remove surplus oil therefrom. The oil not only expels the moisture from each strip but in displacing the moisture fills the pores of the strip.

20 Also after the strip has been treated and dried, the oil on the surface of the strip oxidizes thus forming a smooth moisture proof protective coating for the strip.

The insulator strip when assembled in the 25 rheostat is positioned between the metallic frame or base and the resistance strip which is preferably of the carbon type and is made in accordance with the features of my copending patent application, Serial No. 30 139,784, filed October 6th, 1926.

Also I propose to provide novel arcuate shaped clamp plates associated with the ends of the resistance strip for clamping the resistance and insulator strips to the metallic frame. Each of the plates is provided with a beveled edge for engagement with the contact roller of the contact arm and serves as a seat for the contact roller.

Now, in practice, I find that after an ordinary type of rheostat has been in service for a period of time, and especially if the usage of the same is severe, the contact arm will quite frequently fail to make good contact with the resistance strip due either to wear or distortion of the parts. I propose to remedy this condition by providing a novel contact arm assembly having resilient means for at all times insuring a good contact between the arm and the resistance.

50 In accordance with the general features of

my invention, I provide a cup shaped metallic frame or base in which is disposed my novel contact arm assembly comprising a sliding arm having a slotted portion for receiving a collar connected to the operative shaft of the rheostat and being provided with a bifurcated end for straddling a portion of the contact roller which has a rolling contact with the resistance strip. The sliding frame is resiliently connected to the collar on the 55 shaft by the means of a screw and a spring surrounding the shank of the screw. This spring, as will be more fully described in the accompanying specification, permits of the 60 sliding frame moving relative to the collar. 65

In accordance with other features of my invention, I furnish the cup shaped metallic frame or base with a transparent or celluloid cover which is secured at its center by means of a screw to the end of the rheostat shaft. 70 The outer or peripheral edge of this cover is adapted to engage the external edge of the resistance and insulating strips and the single screw at the center of the celluloid cover serves to not only draw the center of the cover 75 into tight engagement with the end of the shaft but serves to also draw the peripheral edge of the cover into tight engagement with the said strip. The cover also supports the end of the operating shaft thus holding it 80 true with the axis of the frame. Obviously the purpose of the cover is to prevent dust and other foreign matter from interfering with the proper operation of the contact roller. Also by substantially eliminating 85 any dust from the interior of the rheostat, it is possible to prevent change in the resistance of the resistance strip.

Other objects and advantages of my invention will more fully appear from the following detail description taken in connection with the accompanying drawing, which illustrates one embodiment thereof and in which,

Figure 1 is a plan elevation of my novel rheostat;

Fig. 2 is a perspective view of the insulating strip;

Fig. 3 is an enlarged sectional view of my rheostat taken on substantially the line 3-3 of Fig. 4; and

Fig. 4 is a sectional view taken on substantially the line 4—4 of Fig. 3.

Referring now to the drawing in detail, in which like reference numerals designate similar parts throughout the several views, 10 denotes generally a metallic frame or base which is preferably of cup shape. This frame may be made from sheet brass and is preferably a punch press product. Also if it is so desired, the frame may be buffed and nickel-plated.

The cup-like frame or base 10 comprises a flat portion 11 and an annular rim 12. The portion 11 is provided with a central opening 13 through which extends the reduced portion 14 of a thimble 15. The axis of the thimble is disposed parallel to the axis of the frame or base 10. Also the thimble 15 with the shoulder 16 sets tightly and squarely against the frame portion 11.

This thimble 15 may be made on a screw machine and is preferably made from brass rod. It also may be nickel-plated. In order to secure the thimble to the portion 11 of the frame 10, the reduced end 14 of the thimble 15 is riveted at 17 to the portion 11 inside of the cup 10.

Extending through the bore 18 of the thimble 15 is a shaft 20 provided with a reduced portion 19 which projects into the interior of the cup-like frame 10. The shaft 20 has an annular shoulder 21 which engages an annular shoulder 22 formed in the thimble 15. These two shoulders 21 and 22 cooperate to prevent movement of the shaft 20 in one direction.

Also the thimble 15 is provided with an external threaded portion 23 projecting through an annular opening 24 in a mounting panel 25. The frame 10 is tightly clamped to the panel 25 by means of a nut 26 threaded onto the portion 23 of the thimble 15 (Fig. 4). A thin washer 27 is preferably positioned between the nut 26 and the base of the panel 25. Fastened to one end of the shaft 20 is a knob 28 which includes a metallic thimble 29. The knob and thimble are secured to the shaft by means of a set screw 30 extending through an aperture 31 formed in the knob 28. It will be observed from Fig. 4 that the knob 28 includes an annular flange 33 for substantially enclosing the part used to fasten the frame to the panel 25. Also the knob 33 may be made of any suitable insulation, such, for example, as molded phenolic condensation matter.

Surrounding the reduced portion 19 of the shaft 20 is a collar 35, which has an extension 36 telescoping a washer 37. The extension 36 is tightly fitted into the washer or ring-like member 37 and has an annular lateral flange 38 which serves to secure the member 37 to the collar 35. Both the collar 35 and the member 37 as well as the shaft 20 may be made from suitable brass rod. These

parts may also be provided with a mechanical nickel-plate plating. The collar 35 is provided with a pair of cut-away portions 39 and 40 for receiving the legs 41 and 42 of a sliding frame 44. This frame 44, as will be more fully described hereinafter, is adapted to be moved relative to the collar 35.

Legs 41 and 42 of the frame 44 are connected at one end by means of a lateral extension piece 43. This extension piece 43 has an opening 45 through which the shank of a screw 46 extends. Disposed about the shank of the screw 46 is a coil spring 47 preferably of the compression type. One end of this spring abuts the head of the screw 46 and the other end abuts the extension piece 43. This screw 46 is threaded at 48 into the collar 35. Also it should be noted that the screw 46 serves to secure the collar 35 to the shaft 20 as is clearly evident from the illustration in Fig. 4.

Formed integral with the legs 41 and 42 at the other end of the frame 44 is a bifurcated portion 50. This portion 50 includes a slot 49 adapted to receive the reduced portion 51 of a roller 52. The roller 52 is preferably made of brass rod and in reality comprises two rolling portions 53 and 54 connected by the reduced portion 51. Sliding frame 44 may be made from relatively hard brass sheet. Both the frame and the roller are nickel-plated.

Located between the portion 11 of frame 10 and the flange 38 of the extension 36 and surrounding the reduced portion 19 is a spring washer 55. This washer serves to urge the contact arm assembly in a direction away from the panel 25. I have designated the contact arm assembly generally by the reference character 56. It will be evident that this assembly 56 which includes collar 35, sliding frame or arm 44 and roller 52, can be removed with facility from the shaft 20 by releasing the screw 46 from engagement with the reduced portion 19.

Positioned within the cup-like frame or base 10 and abutting the inner periphery of the side 12 is my novel insulating strip 60. I shall describe more in detail the process of making the strip hereinafter. This strip 60 is bent into an arcuate shape when it is mounted in the frame. A resistance strip 61 is also disposed within the cup-like frame 10. This strip is bent into an arcuate shape and is contiguous with the insulating strip 60 which serves to insulate the resistance strip 61 from the frame 10.

Resistance strip 61 is made in accordance with the features of my copending patent application Serial No. 139,784, filed October 6th, 1926. Briefly, this strip consists of a fibrous sheet of material having a coating of my novel resistance paint thereon. The resistance paint or coating consists of a mixture of graphite, lamp black and gum

shellac. In this mixture, I preferably employ 8 pennyweight of lamp black and 7 pennyweight of graphite. These carbons are mixed in a gum shellac solution of from 5 7 to 12 fluid ounces depending upon what resistance is desired. The shellac is preferably diluted with alcohol until it gives a mixture which will read approximately 29° on a Baumé ammonia hydrometer scale. The 10 carbon paint may be applied to the sheet of fibrous material with a suitable varnish brush and then dried for a given period of time at a temperature of 170° Fahrenheit. The advantages of this resistance are fully set out 15 in my copending patent application.

The strip 61 is insulated from the flat portion 11 of the frame 10 by means of an annular gasket or washer 63. This gasket 63 may be made of any suitable insulating material 20 such, for example, as press board. Referring to Fig. 3, it will be obvious that one end of the strip 60 and the corresponding end of the strip 61 are secured to the flange 12 of the frame 10 by means of a screw 65 and a pair 25 of lock nuts 66 and 67. A washer 68 is disposed between the screw 67 and the outer periphery of the portion 12. An aperture 69 is provided in the frame 10 for accommodating the shank of screw 65. Also the screw 30 65 extends through suitable apertures or openings in the associated ends of the strips 60 and 61.

The other end of the strip 60 and the associated end of the resistance strip 61 are secured to the frame by means of a screw 70. 35 This screw extends through an enlarged opening 71 in the annular flange 12 of the frame 10. A bushing 72 is disposed in the enlarged opening 71 and serves to insulate 40 the shank of screw 70 from the frame 10. Screw 70 is locked in place by means of a pair of lock nuts 73 and 74. A pair of washers 75 and 76 are disposed between nut 74 and the flange 12. Washer 75 is preferably made 45 of metal and washer 76 must be made of insulating material so as to insulate the screw from the frame.

In Fig. 2, I have illustrated my novel insulating strip 60. This strip 60 has a pair of 50 apertures or openings 78 for receiving the screws 65 and 70 respectively, as previously described. The resistance strip 61 has a pair of similar openings adapted to be aligned with openings 78. I shall now proceed to 55 scribe in detail my novel clamping plates associated with the heads of the two screws 65 and 70.

I designate the clamping plates by the 60 reference character 80. Since these two plates are identical as to structure, it is believed the description of one will suffice for both. Each of the plates is arcuate in shape so as to accommodate itself to the arcuate shaped strips associated therewith. Also 65 each plate has an aperture 81 through which

the shank of the associated screw extends. Each of the plates has a ground beveled edge 82 adapted to be engaged by the roller 52. In order to insure a good electrical contact between the roller and each of the plates, I 70 preferably make the plates from nickel silver sheets. These plates not only serve as clamps for securing the strips to the frame but also cooperate with the screw heads in limiting the travel of the contact roller. The heads of screws 65 and 70 actually serve as the stops 75 for limiting the travel of the contact roller.

The end of the portion 19 of shaft 20 is reduced at 85 so as to fit in opening 86 in a cover 87. The cover 87 is a circular plate of 80 insulation, and is preferably made of transparent material such as celluloid. The peripheral edge of this cover is adapted to engage the outermost edges of the two strips 60 and 61, as is obvious in Fig. 4. Also the portion 19 of shaft 20 is provided with a threaded opening 88 for receiving the threaded shank 85 of a screw 90. The screw 90 serves to draw the celluloid cover 87 into tight engagement with the shoulder 91 on the shaft 20. Cover 90 90 not only protects the contact mechanism from dust and foreign matter but also protects the parts from moisture.

I shall now describe in detail the process 95 of manufacturing my novel insulating strips 60. The strips 60 are preferably punched from 1/64" press board and are each provided with the previously mentioned pair of perforations 78. Each strip is first boiled in a suitable oil such, for example, as linseed oil. This 100 boiling operation results in the moisture being expelled from the strips and the oil in displacing the moisture fills the pores of the strips. After the strip has been tumbled and dried, it will be found that the oil has 105 oxidized thus providing a waterproof coating for the strip.

In order to remove the surplus oil from the strips, each strip is placed along with others immediately after boiling in a tumbling barrel and tumbled. This tumbling 110 action not only removes the surplus oil from the strip, but also polishes its surface.

The roller 52 is adapted to exert substantially a one pound pressure on the resistance 115 strip; this insures a very positive electrical connection between the roller and the resistance. By adjusting the screw 46, the tension of spring 47 can be varied thus enabling the pressure of the roller to be properly adjusted 120 at all times.

The operation of my novel rheostat is believed to be obvious from the foregoing detail description of the same. By turning the 125 knob on shaft 20, the roller 52 can be made to roll along the surface of the resistance strip 61 to vary the resistance. Any irregularities in the movement of the roller 52 are compensated for by the spring which per- 130

mits the frame 44 to move relative to the collar 35.

I desire it understood that my invention is not to be limited by the above foregoing description but only insofar as defined by the scope and spirit of the appended claims.

I claim:

1. In an electrical current control device, a cup shaped body, a resistance element disposed in said cup shaped body, movable contact means associated therewith and a clamping plate for securing the resistance element to the body, said plate having a beveled edge disposed in the path of movement of said contact means and having tracking cooperation therewith.

2. In an electrical current control device, an arcuate shaped cup constituting the frame of the device, a resistance disposed in the said cup, contact mechanism associated therewith including a contact roller adapted to cooperate with the said resistance, and an arcuate shaped clamping plate for fastening an end of the said resistance to the said cup, said plate having a beveled edge disposed in the path of movement of and cooperable with the roller.

3. In an electrical current control device, a metallic frame comprising a cup shaped member, a resistance strip disposed in the said member, an insulating strip for insulating the resistance from the frame, contact mechanism connected to the frame adapted to cooperate with the said resistance strip, said mechanism including a roller adapted to have a rolling engagement with the resistance strip, and means for clamping the ends of the said strip to the frame, said means including a pair of clamping plates, each of the said plates being arcuate in shape and having a beveled edge disposed in the path of movement of and having tracking cooperation with the roller.

4. In an electrical current control device, a cup-like base, a resistance element disposed in the said base, contact mechanism positioned in the cup base adapted to cooperate with the said resistance element, said mechanism including a resiliently mounted roller adapted to have frictional engagement with the said resistance element, and means for fastening the resistance element to the base comprising a stop for limiting the travel of the said roller and a beveled edged clamping plate drawn upon the resistance element by said stop and tracking the roller into cooperation with the stop.

5. In an electrical current control device having an operating rod and a resistance element, the combination of a collar connected to the said rod, a slidable element associated with the said collar, an adjusting screw for connecting the said element to the collar, resilient means carried by the said screw for permitting the said slidable element to move

relative to the collar, and a roller pivotally connected to the said slidable element adapted to have frictional engagement with the said resistance element.

6. In a device of the class described, the combination of a resistance element, a rotatable operating member having a splayed portion, a yoked member straddling the splayed portion of said operating member and having movement radially of the operating member in a plane intersecting the axis thereof and contact means cooperable with said resistance element and associated with and operated by said yoked member.

7. In a device of the class described, the combination of a resistance element, a rotatable operating member having a splayed portion, a yoked member straddling the splayed portion of said operating member and having movement radially of the operating member in a plane intersecting the axis thereof, contact means cooperable with said resistance element and associated with and operated by said yoked member and means cooperating with said yoked member and yieldingly urging said contact means into contact with said resistance element.

8. In a device of the class described, the combination of a resistance element, a rotatable operating member having a splayed portion, a yoked member straddling the splayed portion of said operating member and having movement radially of the operating member in a plane intersecting the axis thereof, contact means cooperable with said resistance element and associated with and operated by said yoked member, an abutment and a spring interposed between said abutment and said yoked member and yieldingly urging said contact means into contact with said resistance element.

9. In an electric current control device having an operating rod and a resistance element, the combination of a collar, an arm movable with respect to the collar, a contact member carried by the arm, a screw rigidly securing the collar to the operating rod and a spring carried by the screw for yieldingly urging the contact member into contact with the resistance element.

10. In combination, an operating rod, a collar on the rod, an arm movable with respect to the collar, a headed screw rigidly securing the collar to the rod, a lug on the arm, and a spring disposed between the lug and the head of the screw.

11. In combination, an operating rod, a slotted collar on the rod, an arm disposed in the slot in the collar and slidable therein, a headed screw rigidly securing the collar to the rod, a lug on the arm, and a spring disposed between the lug and the head of the screw for yieldingly urging the arm away from the head of the screw.

12. In combination, an operating rod, a col-

lar on the rod having a splayed portion, a branched arm straddling the splayed portion and movable in a plane intersecting the axis of the collar, a cross piece connecting the two branches of said arm, a screw rigidly securing the collar to the rod, and spring means disposed between the head of said screw and said cross piece.

5 In witness whereof, I hereunto subscribe
10 my name this 21st day of September, 1926.

NEWTON C. SCHELLENGER.
